UNITED STATES PATENT OFFICE.

HARRY TEPPER, OF BROOKLYN, NEW YORK, ASSIGNOR TO APEX CHANDELIER CO. INC., OF NEW YORK, N. Y., A CORPORATION OF NEW YORK.

DESIGN FOR A LOOP FOR LIGHTING FIXTURES.

Application filed July 25, 1925. Serial No. 14,217. Term of patent 3½ years.

To all whom it may concern:

Be it known that I, HARRY TEPPER, a citizen of the United States, residing at Brooklyn, in the county of Kings and State of New York, have invented a new, original, and ornamental Design for Loop for Lighting Fixtures, of which the following is a specification, reference being had to the ac-

companying drawing, forming a part thereof.

The figure is an elevational view showing my new design.

I claim—

The ornamental design for a loop for lighting fixtures, as shown.

HARRY TEPPER.
